UNITED STATES PATENT OFFICE.

FRED S. EIKELBURNER, OF LOGANSBRO, INDIANA.

AIR PUMP.

Application filed April 20, 1923. Serial No. 633,460.

To all whom it may concern:

Be it known that I, FRED S. EIKELBURNER, a citizen of the United States, residing at Logansport, in the county of Cass and State 5 of Indiana, have invented certain new and useful Improvements in Air Pumps, of which the following is a specification.

This invention relates to improvements in pumps and more particularly to a special 10 construction for preventing the passage of fluid past the piston of the pump.

The primary object of the invention is to furnish novel means for expanding the cup leather washer of a pump piston and 15 to maintain the cup leather in fully expanded position.

Another object of the invention is to provide a resilient member designed to be applied to an ordinary pump piston and capable 20 of maintaining the cup leather washer of said pump piston in expanded condition at all times, so that the fluid pumped cannot pass between said washer and the casing of the pump.

With the foregoing objects outlined and with other objects in view, which will appear as the description proceeds, the invention consists in the novel features hereinafter described in detail, illustrated in the accompanying drawing and more particularly 25 pointed out in the appended claims.

Referring to the drawing:

Figure 1 is a side view of a pump partly broken away to illustrate the pistons.

Fig. 2 is a detail vertical sectional view 35 of a portion of one of the pump pistons and the casing, and illustrating the improved means for maintaining the cup leather washer in expanded condition.

Fig. 3 is a bottom plan view of the construction shown in Fig. 2.

Fig. 4 is a detail view of the packing expanding member.

In the drawing, 1 designates a pump of any desired construction provided with piston rods 2 and 3 attached to pistons 4 and 45 5. Each of these pistons as best shown in Figures 2 and 3, consist of a small washer 6, a larger washer 7, a cup leather 8 and the improved expanding member 9. These elements are threaded on the lower end of the piston rod and the washer 6 abuts against lugs 10 arranged on the rod, while a nut 50

11 is employed to hold the parts in position.

The cup leather expanding member which really forms the essential feature of the present invention, consists of a circular disk 12 having a central aperture 13 to engage the piston rod and provided at its outer edge 55 with downwardly extending lugs 14. Each of these lugs preferably consists of a bended portion integral with the disk as shown in Fig. 2, and this bended portion forms a pocket to receive the inner end of a curved 60 resilient arm 15. In the embodiment of the invention illustrated, there are three of these arms, and they all extend in an anti-clockwise direction. When the disk 12 is placed on the piston rod, the arms 15 impinge 65 against the inner surface of the cup washer 8, as shown in Figure 3, and owing to the inherent resiliency of said arms, each arm has a tendency to move outwardly away from the center of the disk, so that 70 the skirt portion of the cup leather 8 will be constantly forced toward the inner surface 75 16 of the pump casing.

Prior to the present invention, constructions have been proposed for urging cup 80 leather washers toward the pump casing, but all such constructions are more or less complicated and expensive to manufacture, while the present construction is such that it may be struck from a single piece of sheet 85 metal. Under such circumstances the lugs 14 will be integral with the disk 12 and the arms 13 will be integral with the lugs 14.

Owing to the resiliency of the arms 15, the cup leather will be maintained in contact with the inner surface of the casing, and no fluid will be permitted to pass between the cup leather and the casing. Consequently a pump provided with the improved expanding member, will be more 90 95 powerful and efficient in action than one in which the fluid may pass by the cup leather.

From the foregoing, it is believed that the invention may be readily understood, and it is apparent that changes may be made in 100 the details disclosed without departing from the spirit of the invention as expressed in the claims.

What is claimed and desired to be secured by Letters Patent is:

1. A packing expander comprising a disk,

a plurality of spaced lugs arranged on one side of said disk, and curved resilient arms connected to said lugs and arranged tangentially relatively to the periphery of said disk.

2. In a pump, a piston provided with a cup leather washer, a disk arranged within

said washer and provided with lugs, and resilient curved arms having their inner ends fixed to said lugs and their outer ends 10 yieldingly engaging the inner surface of the skirt of the cup washer.

In testimony whereof I affix my signature.
FRED S. EIKELBERNER.
